UNITED STATES PATENT OFFICE.

JAMES W. McFARLAND, OF BROWNWOOD, TEXAS.

WASHBOILER.

1,271,189.

Specification of Letters Patent.

Patented July 2, 1918.

Application filed February 20, 1918. Serial No. 218,185.

To all whom it may concern:

Be it known that I, JAMES W. McFARLAND, citizen of the United States, residing at Brownwood, in the county of Brown and 5 State of Texas, have invented certain new and useful Improvements in Washboilers, of which the following is a specification.

This invention relates to wash boilers.

The invention has particularly to do with 10 that type of wash boiler in which the water is boiled and a proportion of the steam generated and in which the clothes are subjected to the action of jets of hot water and steam, and a sudden precipitation of the water from 15 the clothes receptacle whereby the dirt is carried off and the clothes are cleansed.

The particular feature resides in an intermittent flow or precipitation of the water from the water receptacle to the clothes receptacle and from the clothes receptacle to the water receptacle. A clothes receptacle is arranged within the water receptacle so that when the water boils up between the two receptacles and a proportion of steam is 25 generated said water and steam will be projected through fine perforations in the clothes receptacle in jets of great intensity, and these jets striking and working through the fabric of the clothes loosen and dislodge the 30 dirt. In order to remove the dirt means is provided which acts after a certain amount of water has accumulated in the clothes receptacle to suddenly release said water whereby it is precipitated down into 35 the water receptacle and this sudden action draws the dirt from the clothes and from the clothes receptacle. This releasing action takes place intermittently so that the clothes are alternately subjected to the jets 40 of hot water and steam and the precipitation of the water from the clothes receptacle.

In carrying out the invention a clothes receptacle is mounted in a water receptacle so that an ample water reservoir is provided between the bottoms of the two receptacles, and a restricted vertical space is had between the two receptacles, the upper end of this space being closed by a steam tight joint. The clothes receptacle has fine perforations 45 communicating with the space between the receptacles. The clothes receptacle has a screened opening in its bottom which communicates with a depending pipe member which may assume the form of a trap or be 50 provided with a valve, and this is termed a releasing device. In operating the boiler 55

the water receptacle is filled to a point above the bottom of the clothes receptacle whereby the releasing device is immersed. When the water begins to boil it will follow the 60 steam up the space between the two receptacles, and said hot water and steam will be projected through the perforations on to the clothes. The top of the clothes receptacle is open and the water from the jets 65 will accumulate in the clothes receptacle. As the water in the water receptacle boils up a certain pressure is exerted on the valve or upon the end of the trap member as the case may be, and a sufficient amount of water 70 must be accumulated in the clothes receptacle before this pressure is overcome. Experience has shown that the said pressure will be overcome quickly and the water in the clothes receptacle will be instantly released, thereby causing a sudden precipitation. 75

The invention will be more readily understood from a reading of the following specification and by reference to the accompanying drawings, in which an example of the invention is illustrated, and wherein—

Figure 1 is a vertical sectional view of an apparatus constructed in accordance with this invention.

Fig. 2 is a horizontal cross sectional view on the line 2—2 of Fig. 1.

Fig. 3 is a view similar to Fig. 1, showing a modified form of a releasing device, and

Fig. 4 is a horizontal cross sectional view 90 on the line 4—4 of Fig. 3.

In the drawings the numeral 1 designates a truncated supporting casing having vents 2 near its upper end and adapted for supporting the boiler on a stove or the like. A 95 cylindrical water receptacle 3 is provided near its central portion with an annular bead 4 which rests on the upper edge of the casing 1 when said receptacle is placed therein. The receptacle 3 has its bottom adjacent the lower end of the casing 1 while its upper end is open and provided with an annular external bead 5. The casing forms a protection for the lower portion of the water receptacle against undue cooling and causes a circulation of heated air over this portion. 100

A clothes receptacle 6 is mounted in the water receptacle. The water receptacle has a short distance below its top an internal 110 annular bead 7 which supports a gasket 8. The clothes receptacle 6 has an external bead

9 at its upper edge which rests on the gasket and the latter fills the space between the two receptacles. Clamps 10 engage over the bead 5 and carry screws 11 which bear 5 on the bead 9 and hold the latter firmly down on to the gasket whereby a steam tight joint is provided. The diameter of the receptacle 6 is such as to provide only a narrow vertical space 12 between the two receptacles. 10 The clothes receptacle has a plurality of minute perforations 13 grouped near its upper end and having communication with the space 12; while other perforations 14 are provided in the lower portion of the 15 clothes receptacle.

The clothes receptacle 6 has a flat bottom 15 and is much shorter than the receptacle 3 so that the bottom 15 is considerably above the bottom of the receptacle 3, whereby an 20 ample water reservoir is provided between the bottoms. At the center of the bottom 15 I provide a screened opening 16 from which a funnel shaped member 17 depends. A U shaped pipe 18 is attached to the bottom 25 of the member 17 and terminates in an elbow 19 which is directed laterally toward said member. The parts 17, 18 and 19 constitute a releasing device and form a trap for holding water in the clothes receptacle until it is released. The releasing device permits of considerable variation in 30 structure.

In operating the wash boiler water is placed in the receptacle 3 until it covers the 35 bottom 15 of the clothes receptacle as indicated by the water line. Soap or other washing agents is placed in the boiler and the clothes to be washed are then deposited in the receptacle 6. Heat is applied under the 40 water receptacle and within the casing 1 and the water caused to boil and the soap dissolved. The water at the lower end of the space 12 will boil first and a proportion of steam will be generated with the result that 45 said steam and water rise in the space 12 as the boiling continues. The steam and hot water will first be projected through the perforations 14, but as the boiling increases the steam and water will rise in the space 12 50 and be projected through the perforations 13 with great intensity or force, all of said jets converging toward the center of the clothes receptacle and forming a spray which acts on the clothes and spouts through the fabric 55 of the same with considerable force.

As the water boils a certain pressure will be exerted on the open end of the elbow 19 and thus no water will pass from the clothes receptacle down through the parts 17 and 60 18 until sufficient water has been accumulated in the clothes receptacle to overcome the said pressure. When the pressure is overcome and the water released the action will be sudden. Up to the time this releasing 65 action takes place the jets will continue

and their intensity gradually increases; however the instant the water in the clothes receptacle is released the jets cease and as the water is precipitated or rushes from the receptacle 6 down through the parts 17 and 70 18 and escapes from the part 19, the water also recedes in the space 12. It is apparent that this sudden releasing of the water tends to draw the dirt not only from the clothes but to carry it down with the water. The 75 jets loosen the dirt and the releasing action carries it off. Immediately following the releasing action the water in the space 12 begins to boil up and is again projected in jets. This action is again followed by the 80 releasing action and the operation continues as long as the heat is maintained and sufficient water remains in the receptacles.

As stated the releasing device permits of varied construction so long as a depending 85 pipe or tubular member is used and this invention contemplates the use of a depending pipe or tubular member in all its forms. As illustrating one of the variations a modified form of releasing device is shown in Figs. 90 3 and 4. All the parts are the same as in Figs. 1 and 2 with the exception of the omission of the parts 18 and 19. An elbow 20 is attached to the lower end of the member 17, and the lateral end of the elbow terminates in a flared mouth 21 covered by a screen 22 and containing a ball valve 23. Pressure acting on the valve 23 seats the same 95 against the end of the elbow and obstructs the downward flow of water through said elbow. When the weight of the water in the clothes receptacle and the parts 17 and 20 is sufficient to overcome the pressure the ball is dislodged and rolls down against the screen 22, whereby the water is released. The flaring mouth provides an area over 100 which the pressure may act laterally in seating the valve.

The foregoing description and illustration clearly express the invention, but it is 110 to be understood that said illustration is merely an exemplification and the invention may be carried out in various other ways.

What I claim is,

1. In a wash boiler, a water receptacle, a 115 clothes receptacle mounted in the water receptacle and having its bottom some distance above the bottom of the water receptacle, whereby a water reservoir is provided below the clothes receptacle, the 120 clothes receptacle being slightly spaced from the water receptacle, whereby a vertical space is provided between the receptacles, a steam tight joint between the receptacles located at the upper end of the space there- 125 between, the clothes receptacle having a plurality of minute perforations in its side walls communicating with the space between the receptacles, the clothes receptacle having an opening in its bottom, and a water holding 130

and releasing device depending from the opening in the bottom of the clothes receptacle and comprising a tubular member having its discharge end opening into the water reservoir formed between the bottoms of the two receptacles.

2. In a wash boiler, a cylindrical water receptacle having an internal projection near its upper end, a supporting casing surrounding the lower portion of the water receptacle, a gasket mounted on the projection within the upper end of the water receptacle, a cylindrical clothes receptacle having its upper ends resting on the gasket within the water receptacle, means mounted on the water receptacle for clamping the upper end of the clothes receptacle on the gasket where-

by steam tight-joint is had, the clothes receptacle being slightly spaced from the water receptacle to form an annular vertical space therebetween closed by the steam-tight joint at its upper end, the clothes receptacle having a plurality of minute perforations grouped together at the upper end of the space between the receptacles, an opening in the bottom of the clothes receptacle, and a tubular water holding and releasing member depending from the opening and having a laterally directed discharge opening below the bottom of the clothes receptacle. 20 25 30

In testimony whereof I affix my signature.

JAMES W. McFARLAND.
